UNITED STATES PATENT OFFICE

2,532,963

COMBINED CLOCK AND LOUD-SPEAKER
UNIT

Grathy O. Tanner, Houston, Tex.

Application September 28, 1948, Serial No. 51,609

2 Claims. (Cl. 181—31)

1

This invention relates to improvements in a combined clock and loud speaker unit.

An object of the invention is to provide an improved form and construction of clock and loud speaker unit.

Another object of the invention is to provide an improved form and construction of clock and loud speaker unit which will be housed within a combined casing or housing for supporting a clock and a loud speaker which will be mounted rearwardly of the clock and in spaced relation thereto.

A further object of the invention is to provide an improved clock and loud speaker unit which will be so arranged and constructed that the back of the clock and the cone of the speaker will lie in spaced parallel relation for directing the sound waves, such as voice and musical programs, through a plurality of grills forming a part of the supporting casing or housing for the clock and speaker.

A still further object of the invention is to provide a combined clock and speaker unit which will be so positioned and arranged that persons listening to programs from the speaker will automatically look in the direction from which the music is coming and thus be caused to look at the dial of the clock forming a part of the unit, thereby noting the time of day or night.

Another object of the invention is to provide an improved form of clock and speaker unit which will be housed within a suitable baffle casing or housing, said unit being highly efficient in operation and relatively inexpensive to manufacture and produce.

Other objects will appear as the description proceeds.

In the accompanying drawings which form a part of this application:

Figure 1 is a front elevation of the combined clock and speaker unit;

Figure 2 is a vertical sectional view through the combined clock and speaker unit;

Figure 3 is a perspective view of the upper bracket member used for supporting the speaker within the baffle casing, and

Figure 4 is a perspective view of the lower bracket member used for supporting the speaker within the baffle casing.

Like characters of reference are used throughout the following specification and the accompanying drawings to designate corresponding parts.

In carrying out the invention, there is shown and provided an improved form and construc-

2

tion of combined clock and speaker unit including a baffle casing or housing generally designated by the reference numeral 1 of integral construction, the same being open as at 2 at its rear or back for contacting a vertical supporting wall (not shown), and said casing or housing 1 being of substantially square or rectangular shape in cross section.

The top 3 of the casing or housing 1 and the bottom 4 thereof extend in parallel relation, as do the opposite vertical sides 5 and 6. The top 3 extends forwardly a considerable distance beyond the bottom 4, thus providing a downwardly and inwardly extending inclined front 7 of substantially rectangular shape.

A circular opening 8 is formed centrally in the front 7 of the casing or housing 1, the same being formed with an annular interiorly positioned seat 9 about its periphery, as best seen in Figure 2 of the drawings. A plurality of circumferentially disposed grilles 10 are formed through the front 7 of the casing or housing 1 about said centrally disposed central opening 8, and said grilles 10 being separated by the radially extending intervening web portions 11.

A clock 12 having a conical back end 13 and circular face 14 formed with a forwardly extending peripheral supporting flange 15 is adapted to be positioned within the central opening 8 of the front 7 in contact with a circular clock dial or face protecting crystal 16 whose peripheral edge is adapted to seat within the annular seat 9 formed about the opening 8. The front edge of the flange 15 being in locking contact with the rear edge of the crystal 16 for supporting the same in position. The usual hour and minute hands 17 and 18 will be supported for rotation upon the usual arbors 19.

A loud speaker generally designated by the reference numeral 20 and having the usual cone diaphragm 21 and permanent magnet 22 will be supported by the upper and lower L-shape bracket members 23 and 24, secured to the inside surfaces of the top 3 and bottom 4 of the casing or housing 1 by means of the screw fasteners 25, while the screw fasteners 26 will extend through the inner ends of the bracket members 23 and 24 and into the speaker 20, thus holding the same in fixed position in spaced relation directly to the rear of the conical back end 13 of the clock 12, with the cone diaphragm 21 and the said conical back end 13 of the clock 12 being in parallel relation one with the other, thus providing a parallel walled sound passage for directing the program from the speaker 20 directly to and through the circumferentially

arranged grills 10 in the front 7 of the casing or housing 1. Since the audible programs from the speaker 20 will be heard from the immediate proximity of the clock dial or face 14, persons hearing the program will naturally look for the source of the program and will automatically see the clock and note the time of day or night.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A combined clock and loud speaker unit including a housing of substantially rectangular shape in cross section having a downwardly and rearwardly sloping front formed with a centrally disposed circular opening therethrough, an annular seat formed about the periphery of said opening in the rear portion thereof, a clock crystal supported upon said seat, a clock mounted in said opening having a face formed with a forwardly extending peripheral flange adapted

to engage said crystal and be received in said annular seat, said clock having a rearwardly extending conical back, grills formed in said housing front about said central opening, and a loud speaker supported in said housing in axial alignment with said clock in spaced relation and to the rear thereof.

2. The subject matter as claimed in claim 1, detachable L-shape bracket members attached respectively to the inside surfaces of the top and bottom of said housing and to said loud speaker for mounting the same, and the diaphragm of said speaker being in spaced parallel relation with the conical back of said clock forming a directional sound passage for directing the sound from said speaker to and through said grills.

GRATHY O. TANNER.
